Att 292 Ex

OR U 3,349

— S.B. Rowley, —
— Design for Glass Cover for —
— Fruit Jars. —

Nº 3349

FIG. 1.

PATENTED
JAN 19 1869

FIG. 2.

FIG. 3.

United States Patent Office.

S. B. ROWLEY, OF PHILADELPHIA, PENNSYLVANIA.

Design No. 3,349, dated January 19, 1869.

DESIGN FOR THE GLASS COVER OF A FRUIT-JAR.

The Schedule referred to in these Letters Patent and making part of the same.

To all whom it may concern:

Be it known that I, S. B. ROWLEY, of the city and county of Philadelphia, State of Pennsylvania, have originated a new Design for a Glass Cover for a Fruit-Jar; and I do hereby declare that the accompanying drawing, and following explanation thereof, form a full, clear, and exact description of the said design.

In the drawing—

Figure 1 represents a section of the cover,

Figure 2, a plan view, and

Figure 3, an inverted plan view.

The cover has a recess, *a*, in the top, bounded by an annular rib, *b*, the outer edge of which is depressed, so as to form a ledge or shoulder, *d*.

In the centre of the recess *a* is a projection, *e*, of the form shown in fig. 1.

In the under side of the cover is an annular recess, *f*, bounded by a circular rim, *h*, the under side of which is bevelled on both sides, so as to be reduced to a comparatively sharp edge.

I claim the design for a glass cover for fruit-jars, substantially as described, and represented in and by the accompanying drawing.

In testimony whereof, I have signed my name to this specification, in the presence of two subscribing witnesses.

S. B. ROWLEY.

Witnesses:

JOHN WHITE,
O. B. PRICE.
